UNITED STATES PATENT OFFICE.

CALEB T. REEDER, OF STEWARDSON, ILLINOIS.

WASHING-MACHINE.

SPECIFICATION forming part of Letters Patent No. 665,181, dated January 1, 1901.

Application filed March 19, 1900. Serial No. 9,281. (No model.)

To all whom it may concern:

Be it known that I, CALEB T. REEDER, a citizen of the United States, and a resident of Stewardson, in the county of Shelby and State 5 of Illinois, have invented a new and Improved Washing-Machine, of which the following is a full, clear, and exact description.

This invention relates to a washing-machine of that class in which plungers are employed to create a suction through the clothes, whereby to accelerate the process of washing the clothes.

This specification is the disclosure of one form of the invention, while the claim defines 15 the actual scope thereof.

Reference is to be had to the accompanying drawings, forming a part of this specification, in which similar characters of reference indicate corresponding parts in all the views.

Figure 1 is a plan view of the machine with a part of the cover broken away. Fig. 2 is a vertical section of the machine. Fig. 3 is a similar view showing the parts in inactive position, and Fig. 4 is a bottom plan view of the 25 plunger.

The machine has a body or reservoir *a*, which may be of any desired construction rendering it water-tight. This body may be supported on legs *a'* and provided at its side with 30 a box *a''* (see Fig. 1) for containing soap and other articles useful in connection with the operation of the machine. At the top of the body *a*, near the rear side thereof, a beam or bar *b* is placed rigidly, and this beam carries 35 the cover *b'*, which is adapted to close the box. This cover may be formed in one or two sections, as desired. Within the reservoir *a* is situated a preferably cylindrical pan *c*, the bottom of which is perforated. This pan is 40 supported on cleats *a''*, situated in the bottom of the reservoir *a*, as shown, so that the water may circulate freely under the pan *c*. The sides of the pan *c* are also perforated, as illustrated. The pan *c* is removably held in place 45 by keepers *c'*, which may be of any desired form.

Fastened to the middle portion of the bar *b*, at the top thereof, is a plate *d*, on which is pivoted a standard *d'*. The standard *d'* has 50 a pivoted brace *d''* attached thereto, the lower end of the brace being removably seated in a suitable keeper *d'''*, formed on the plate *d*. By

means of this brace the standard *d'* may be supported in the perpendicular position shown in Fig. 2, and when desired the brace *d''* may be thrown out of the keeper *d'''*, permitting the standard *d'* to fall back to the position shown in Fig. 3. The front side of the standard *d'* is formed with a number of notches, which are adapted to have seated therein a pin *e'*, carried on the inner end of a hand-lever *e* and forming the fulcrum thereof. The hand-lever *e* is preferably formed of two side members fastened rigidly together by bars *e''*, situated, respectively, at the ends 60 of the lever. The bar *e''* at the inner end of the lever *e* is therefore in juxtaposition to the pin *e'*, which forms the fulcrum of the lever, and for holding the lever with its fulcrum-pin *e'* in the desired notch of the standard *d'* 65 I provide a lock-bar *f*, which is removably held in guides *f'*, attached to the standard *d'*. It will therefore be seen that the lever *e* may be placed at any desired position on the standard *d'*, so as to adjust the plunger relatively 70 to the amount of clothes contained in the pan *c*, and it will also be observed that by mounting the lever in this manner it is free to swing up and down to properly actuate the plunger.

The plunger has a cylindrical main or central portion *g*, which is arranged to reciprocate vertically through an opening *b''* in the cover *b*. The upper end of this main portion *g* of the plunger is connected by a suitable shackle *g'* with the hand-lever *e*, so that the movement of the lever is transmitted to the plunger. The central portion *g* of the plunger has an open lower end, and this portion of the plunger extends down into the pan *c*. The central portion *g* of the plunger carries 80 an approximately-conical-shaped skirt *g''*, having a vertically-disposed marginal flange *g'''* terminating in a plane coincident with the plane of the lower edges of the central portion *g* of the plunger. The central portion *g* and the skirt *g''* of the plunger are provided 85 with a number of rigid strips *g'''*, which are preferably fastened to the parts *g* and *g''* and have their lower edges level with the lower edges of such parts. These strips *g'''*, together with the lower edges of the parts *g* and *g''*, serve as beaters for engaging the clothes, and the plunger when forced downward upon the clothes presses them against the bottom of 90 95 100

the pan *c*. Then upon the return of the plunger a suction is created in the bottom of the reservoir *a*, and this tends to materially assist in the process of cleaning the clothes. 5 The plunger keeps the water in constant circulation, causing it to pass in and out of the pan *c*, as will be understood.

Various changes in the form, proportions, and minor details of my invention may be resorted to without departing from the spirit and scope of my invention. Hence I consider myself entitled to all such variations as may lie within the scope of my claim.

Having thus described my invention, I 15 claim as new and desire to secure by Letters Patent—

A washing-machine, having a reservoir, a

plunger working therein, a notched standard pivotally mounted on the reservoir, a removable brace for holding the standard in operative position, a lock-bar removably mounted on the standard in front of the notches, and a hand-lever connected with the plunger and having a fulcrum-pin capable of being seated in any one of the notches, the fulcrum- 20 pin being held in place by the lock-bar. 25

In testimony whereof I have signed my name to this specification in the presence of two subscribing witnesses.

CALEB T. REEDER.
